UNITED STATES PATENT OFFICE

CHARLES J. ODEND'HAL, OF BROOKLINE, MASSACHUSETTS

PRESSURE-CONTROL VALVE

Application filed November 26, 1927. Serial No. 235,873.

The present invention relates to a pressure regulating valve adapted to maintain a constant pressure in a steam or other fluid feed line between the pressure actuated mechanism and pressure generating device.

An object of the invention is to provide a device of this character embodying a balanced valve responsive to the variations of the pressure in the feed line whereby to control communication therebetween under certain predetermined conditions and including spring tension means operatively connected with the valve and arranged for closing the same upon the creation of a uniform pressure within the feed line at each side of the valve.

A further object of the invention is to provide novel tension adjusting means interposed between the valve and the spring and arranged to automatically maintain a uniform tension upon the valve by the spring during the expanding and contracting of the spring caused by the opening and closing of the valve.

A still further object is to provide means for manually adjusting the tension of the spring so as to maintain the valve in a proper responsive condition with respect to the pressure of the fluid.

Another object is to provide an apparatus of this character of simple and practical construction, which is efficient and reliable in performance, which is devoid of any delicate or sensitive mechanism apt to easily become out of order, in which the spring tension adjusting mechanism associated with the valve is disposed outwardly with respect to the feed line thus permitting of the ready disassembling thereof for replacement of the parts when necessary which is inexpensive to manufacture and install in operative position and otherwise well adapted for the purpose for which the same is intended.

Other objects and advantages resides in the special construction and combination of the various elements comprising the invention, reference being had to the accompanying drawings forming a part hereof, wherein:

Figure 1 is a vertical sectional view through the valve assembly showing the invention adapted for use as a pressure regulator and

Figure 2 is a similar view with the upper structure broken away and showing the adaptation of the device for use as a release valve.

Referring now to the drawing in detail, the invention comprises a valve housing indicated at 5, open at each end and constituting intake and discharge ports 6 and 7 respectively for the housing. Within the housing is a partition 8 closing communication between the intake and discharge ends thereof, said partition having an opening 9 the edges of which are formed into a valve seat upon which the valve 10 is operatively arranged.

One side of the valve is provided with a valve stem 11 disposed within the intake end of the housing with its end extending laterally from the housing through an opening formed in the upper end plate 12'. The opposite face of the valve 10 also carries a stem 13 on the end of which is mounted a piston 14 operatively positioned with a cylindrical section 15 formed in the housing, the head of the piston remote from the valve being spaced substantially from the lower end plate 12. The compartment indicated at 17 thus formed between the head of the piston and the casing communicates with the intake end of the housing by way of a passage 18.

The end of the stem 11 protruding from the casing is fitted with a suitable packing nut 19, a cap 20 being threadedly attached to the outer end of the stem, to which cap is also attached an outwardly extending rod 21 having its free end formed with a cross head 22 engaged for limited movement within slotted openings 23 formed in a pipe 24, said pipe being attached to an upper spring compressing plate 25 having its outer edges formed into guides 26 slidably mounting the guides and plate within a pair of guide rods 27.

A lower spring compressor plate 28 is disposed between the rods 27 having a central opening 29 permitting free movement with respect to the rod 21, said plate constituting an abutment for the opposite end of a coil spring 30 pressurably retained therebetween.

A collar 31 is arranged on each of the guide

rods 27 adjacent the lower end thereof each of said collars having an inwardly extending support 32 to the inner end of which is pivotally mounted a roller bracket 33, each bracket rotatably supporting upper and lower rollers 34 and 35 respectively. The upper rollers 34 are arranged in engagement with the under side of the lower plate 28 with the lower rollers 35 engaging the beveled edge 36 of the cap 20.

The upper plate 25 is adjustably retained in position by reason of its threaded engagement with a screw 37 extending from the upper face of the plate and provided with a pair of spaced flanges 38 engaging the opposite surfaces of a plate 39 secured at the upper end of the guide rods 27. The upper end of the screw 37 carries an adjusting wheel 40 through the manipulation of which the plate 25 may be adjusted whereby to regulate the tension of the spring 30.

The tension of the spring 30 may thus be adjusted to enable the same to close the valve when the pressure in the opposite end of the housing is equal and permitting the opening of the valve upon a variation in such pressure, the valve thus comprising, in effect, a balanced valve. Upon a decrease in the pressure in the feed pipe connected with the discharge end of the valve housing 7, the pressure in the opposite end of the feed line will operate to open the valve by reason of the application thereof against the under side of the piston 14, which represents a greater pressure responsive surface than the upper side of the valve because of the area occupied by the stem 11. This difference in the surface exposed to the pressure between the piston and valve will be sufficient to enable the upward movement of the valve against the tension of the spring 30 and thus permit the pressure to the feed line to be uniformly maintained. As soon as the pressure in the discharge end of the housing 7 reaches a point equal to that in the opposite end of the housing the spring will operate to close the valve.

After being adjusted to its desired tension, the spring 30 is maintained at a uniform tension with respect to the valve by means of the pivoted roller bracket 33 interposed between the cap 20 and the lower spring plate 28. These brackets 33 are arranged to have their free ends swung upwardly during the upward movement of the valve and it will be apparent that during such swinging movement the spring 30 will be contacted during the initial movement of the bracket into its uppermost position. This increased tension of the spring however is counteracted by the decrease in the force required by the valve in moving the brackets as the same approach and move beyond their uppermost position.

This compensating arrangement is brought about by reason of the leverage principle

on which the brackets operate, it being well known that a greater force will be required to initially move a member from its position as shown by the brackets 33 in Figure 1, that will be required as the same approaches its upper position. The decrease in such force required to raise the valve will accordingly be offset by the increase in the tension of the spring, thus serving to maintain the balanced relationship between the valve and the spring irrespective of the extent of movement of the valve. The rollers 34 and 35 carried by the bracket provide an anti-friction engagement for the bracket between the cap 20 and plate 28.

The valve control mechanism may also be effectively used in connection with a reducing valve by rearranging the position of the valve in the manner as shown by Figure 2 of the drawings. In such construction the valve is balanced as heretofore described although the valve is disposed operatively in feeding position from the arrangement shown in Figure 1.

This construction for the reducing valve provides for the entrance of the fluid under pressure at the intake end 41 of the housing and for discharge therefrom through the opening 42 at the opposite side thereof as shown by the arrows. The valve is normally held open by the action of the spring and as the pressure in the feed pipe communicating with the discharge end 42 approaches that desired, the valve will gradually close.

The purpose of the reducing valve is to provide means enabling a reduced pressure to be maintained in the feed line connected with the discharge end 42 of the housing and for this reason the passageway 43 communicating with the chamber 44 beneath the plunger 45 is arranged in connection with the discharge end of the housing. The pressure against the adjacent faces of the valve and the plunger will be equal and because of the construction of such surfaces of an equal area, the movement of the valve will be unaffected by the pressure admitted through the intake end 41. On the other hand the opposite faces of the piston and valve present a different area, due to the area occupied by the stem 11 extending from the upper surface of the valve and because of this fact, as soon as the pressure in the discharge end 42 reaches an amount sufficient to offset the tension of the spring, the valve accordingly will be closed.

While the invention is adapted primarily for use in connection with said steam feed line, it is to be understood that the device is equally well adapted for use in connection with other fluid pressure pipe line, such as water, gas or other fluid.

It is apparent that since the pressure necessary to close the valve is regulated by the size or diameter of the valve stem the relative difference in the pressure at the opposite

end of the housing will thus be governed by the size at which the stem is constructed.

It is obvious that the invention is susceptible of various changes and modifications, without departing from the spirit or scope of the invention or sacrificing any of its advantages, and I accordingly claim all such forms of the device to which I am entitled.

Having thus described my invention, what I claim as new is:

1. In a pressure control valve, spring actuating means for the valve adapted to permit opening thereof under certain predetermined pressure condition and including tension compensating means for the spring interposed between the spring and the valve comprising a pair of pivotally mounted roller brackets having their free ends arranged for maintaining the adjacent ends of the spring and valve in spaced relation and adapted upon their upward swinging movement to increase the tension of the spring without subjecting the valve to such increased tension.

2. In a pressure control valve, spring actuating means for the valve adapted to permit opening thereof under certain predetermined pressure condition and including tension compensating means for the spring interposed between the spring and the valve comprising a pair of pivotally mounted roller brackets having their free ends arranged for maintaining the adjacent ends of the spring and valve in spaced relation and adapted to transmit movement of the valve to the spring for expanding and contracting said spring, the initial upward swinging movement of the bracket for contracting the spring serving to increase the tension of the same, said spring being unaffected by a continuous upward movement of the bracket whereby to limit the increase in the tension of the spring during the opening of the valve.

In testimony whereof I affix my signature.
CHARLES J. ODEND'HAL.
